UNITED STATES PATENT OFFICE.

PERCY BLOOM, OF NEW YORK, N. Y.

CHIMNEY-VENTILATOR.

933,051.

Specification of Letters Patent.

Patented Sept. 7, 1909.

Application filed March 17, 1909. Serial No. 484,031.

To all whom it may concern:

Be it known that I, PERCY BLOOM, a citizen of the United States, and resident of New York, borough of Brooklyn, in the county of Queens and State of New York, have invented certain new and useful Improvements in Chimney-Ventilators, of which the following is a specification.

This invention relates to improvements in chimney ventilators.

In the drawings: Figure 1 is a side view of a ventilator constructed in accordance with this invention. Fig. 2 is an enlarged vertical sectional view of a ventilator constructed in accordance with this invention. In this figure the parts are separated and drawn closer together. Fig. 3 is a sectional view of the locking cap, pivot pin and hood assembled. Fig. 4 is a sectional view of the pivot pin and hood with the locking cap raised above. Fig. 5 is a sectional view of the hood with the pivot pin and locking cap above in separated position. Fig. 6 is a plan view from underneath the locking cap. Fig. 7 is a plan view from above of the weather hood. Fig. 8 is a side view of the lower end of the spindle showing an alternative construction, the cap being shown in section.

The principal objects which the present invention has in view are; to provide a mechanism which may be readily and quickly lubricated; to provide a mechanism which may be quickly and easily dis-assembled for repair or replacement; and to provide a long wearing pivot for the revolving structure.

With these objects in view, the construction consists in substituting for the usual solid rod or spindle, the present hollow pipe spindle —2—. This is of any desired length, and is provided at the lower end with the slightly cupped shape, shown in Fig. 2 of drawing,—to more closely fit the pivot ball —3—. The pivot ball —3— rests within the upper edges of the depression —4—. The depression —4— serves to maintain the ball —3— in oil as long as the cup —5— contains oil. It further serves to maintain the center location of the ball —3—. The cup

—5— is formed of any desired size and of a shape substantially as shown in the drawings. The spindle —2— is maintained in its central and vertical position by the pivot pin —6—, which is mounted in a perforation which is extended through the top of the hood —7—. The pivot pin —6— closely fits within the tubular spindle —2—, and is provided with the extensions —8— which fit within the recesses —9— in the top of the hood —7—. By means of the extensions —8— the pin —6— is prevented from rotating and thereby causing any loosening action upon the screw cap —10— when the same is placed in position. The perforation through which the pin —6— is inserted extends through the boss —11— set up from the cap —7—.

The boss —11— is provided with the flanges —12—. It is under these flanges that the extensions —13— with which the cap —10— is provided, extends. To permit the extensions —13— to pass the flanges —12—, the said flanges are cut away at —14—. The flanges —12— may, if desired, be constructed with an inclined under surface, which produces the effect of drawing the cap —10— hard down upon the top of the pin —6—. In this position of the cap —10— the pin —6— and the spindle —2—, the rotary parts of the present device are held firmly in their operative positions.

As in the ordinary construction, the spindle —2— is provided with the lifting fan blades —15—, fixedly mounted thereon in any suitable manner. The spindle —2— with the blades —15—, are caused to rotate by the cowl shown in Fig. 1. The cowl consists in a number of wind vanes —16— which are rigidly mounted on the head —17— and the framing rod —18—, to receive the wind with a glancing effect on the one side of the vertical central line of the cowl; and with a driving effect on the opposite side, whereby the cowl is rotated by the wind.

The blades —15— are so shaped and inclined from the vertical as to operate as an exhaust fan when the cowl is rotated by the wind. The construction of the cowl and

fan, and the operation of the same are not new with me, but are to be found in any of the well known constructions of the present day.

5 The cup —5— is mounted in the center of the chimney —20— on spider arms —21—, which are formed integrally with the cup —5— and are riveted to the chimney —20— at —22—. Secured to the chimney —20— 10 are the arms —23—. To the upper end of the arms —23— is secured the hood —7—, side flanges —24— being formed in the said hood to receive the ends of the arms —23—. The arms —23— are held between the flanges 15 —24— in any suitable manner,—that herein shown being by means of screws —25—.

When assembling the device as described, the spider —21— bearing the cup —5— is placed in position on the chimney —20— and 20 riveted thereto. Within the cup —5— is then placed the ball —3—. Upon the ball —3— is seated the lower end of the spindle —2— which carries the fan —15— and the head —17— with the vanes —16—.

25 The arms —23— are riveted to the chimney —20—, and the upper end of the arms are placed in position to be screwed to the weather hood —7—, as shown. The arms —23— may be attached to the chimney 30 —20— in advance of the placement of the spindle —2— and its connected parts.

When the spindle and parts carried thereby are in position, the hood —7— is inserted between the upper end of the arms —23— 35 and secured thereto by the screws —25—. The pin —6— is now introduced through the perforations in the boss —11— and into the upper end of the spindle —2—. The extensions —8— are inserted in the recesses 40 —9—. The cap —10— is then adjusted so that the openings —14— in the flange —12— register with the extensions —13—. This register permits the flange —12— to 45 pass above the extensions —13— in such position that when the cap —10— is rotated the said flanges extend over the said extensions and cause the cap to bear down upon the top of the pivot pin —6— to hold the same firmly in position.

50 To dis-assemble the parts, the operation just described is reversed in that the cap —10— being removed, the pin —6— may be withdrawn, the hood —7— be disengaged from the arms —23— and removed, when 55 the spindle —2— with its connected vanes —16— and the fan —15— may be drawn from the top of the chimney —20—.

It is most desirable that the ventilator 60 should rotate with as little friction as possible, and to accomplish this, the pivot on which it turns must be well lubricated. It is not practical in the position in which the device is placed exposed to the weather to 65 mount the same upon any delicate bearings such as the popular type of anti-friction

bearings. In the usual constructions in use today, it is necessary to remove the fans and vanes to lubricate the pivot. This I avoid in the present invention by feeding the oil to the pivot point through the hollow spindle —2—. To do this with the construction here described requires nothing more than that the cap —10— and pin —6— be removed. This exposes the open top of the tubular spindle —2—. The spindle is filled 70 with a suitable lubricant and the pin —6— and cap —10— are replaced. This operation, it will be understood, would not involve more than a few minutes at a time.

The lubricant I prefer to use is a heavy 80 oil. It will be understood, however, that the mechanism here shown is of such character that any of the lubricating greases could be used.

As the vanes —16— are rotated, the ball 85 —3— forms the pivot on which the spindle —2— turns. The spindle being filled with the lubricant, the joint is constantly lubricated. Gradually the oil passes the joint and in doing so escapes into the cup —5—, 90 lubricating the joint between the ball —3— and the edge of the spindle. The lubricant passes into the recess —4— under the ball —3—. Gradually the lubricant originally placed in the spindle —2— passes into the 95 cup —5— and fills the same. In this condition, and as long as the oil remains in the cup —5—, the pivot for the spindle works in oil. When in the course of time it again becomes necessary to re-oil the 100 device, this is accomplished by repeating the operation above described.

In Fig. 8 of the drawings I have shown a construction wherein a solid steel point —26— is used in place of the ball —3— 105 heretofore described. In this construction the steel point —26— is driven into the lower end of the spindle —2— and shaped as shown. To feed the lubricant to this point the spindle is provided with a perforation —27— in the side and at the lower end of the tubular portion. Through this perforation the lubricant passes to the cup —5— and the recess —4—.

Having thus described this invention, 115 what is claimed is:—

1. A chimney ventilator comprising an open ended tubular support provided with wind vanes and an exhaust fan, a pivot pin inserted in the upper end of said support, 120 a hood to hold said pin against rotation and adapted to cover the upper end of said support, a ball bearing located at the lower end of said tube and serving to close the end of same whereby said tube is converted into 125 a reservoir for oil to serve to lubricate said bearing.

2. A chimney ventilator comprising an open ended tubular support provided with wind vanes and an exhaust fan, a pivot pin 130

inserted in the upper end of said support, a hood to hold said pin against rotation and adapted to cover the upper end of said support, a cup shaped reservoir located at the 5 lower end of said tubular support, a ball bearing located between said reservoir and the lower end of said tube and serving to close the same, substantially as set forth.

Signed at New York in the county of New York and State of New York this 13th 10 day of March A. D. 1909.

PERCY BLOOM.
